(57) **CLAIM**

The ornamental design for a component of a mount for a digital video camera, as shown and described.

DESCRIPTION

FIG. 1 is a perspective view of a first embodiment of a component of a mount for a digital camera; said component being a flat mount disc.

FIG. 2 is a top view of the first embodiment.

FIG. 3 is a side view of the first embodiment.

FIG. 4 is a perspective view of a second embodiment of a component of a mount for a digital camera; said component being a curved mount disc.

FIG. 5 is a top view of the second embodiment; and,
FIG. 6 is a side view of the second embodiment.
